CALIFORNIA.

SPARK PLUG.

Application filed September 26, 1921. Serial No. 503,162.

To all whom it may concern:

Be it known that we, WILLIAM H. CHARD and WILLIAM F. HILLS, citizens of Canada and the United States, residing at Paicines and Mountain View, respectively, in the counties of San Benito and Santa Clara and State of California, have invented new and useful Improvements in Spark Plugs, of which the following is a specification.

10 This invention relates to igniting devices for internal combustion engines especially those employed in the jump spark plug ignition systems and commonly termed spark plugs.

15 The principal object of this invention is to provide a spark intensifying device made as a part of the spark plug so as to obtain a stronger and sure spark of the plug at all times.

20 Before the development of this device spark plugs have been more or less unreliable at times due to the fact that they become foul which generally impaired their proper functioning and often caused them 25 to be totally useless, until they were cleaned and otherwise adjusted. With our invention, however, these conditions are taken care of by remedying or rather removing the conditions which cause the trouble.

30 Other objects and advantages will be apparent during the course of the following description.

In the accompanying drawings forming a part of this specification, and in which like numerals are employed throughout the same,

Fig. 1 is a vertical section of our spark plug taken on the line 1—1 of Figure 2,

Fig. 2 is a plan view,

40 Fig. 3 is a detail view in side elevation of the porcelain core of the plug,

Fig. 4 is a view in horizontal section through the head of the plug,

Fig. 5 is a detail view of the grounding 45 clip, and

Fig. 6 is a perspective view of the plug as assembled.

In the accompanying drawings wherein for the purpose of illustration is shown a 50 preferred embodiment of our invention, the numeral 1 represents the metal sleeve having a collar 2 at one end and a threaded opposite end 3 to be received in the spark plug opening of the engine cylinder. The 55 central bore of the sleeve is threaded inter-

nally of the collar 2 to receive the threaded metal bushing 4 which in turn is carried upon the stem 5 of the porcelain core. The porcelain also has an annular ring 6 which is seated on the shoulder 7 within the sleeve 60 so that the porcelain may be secured in the sleeve by screwing down on the bushing 4 and holding the ring 6 on its seat. The remainder of the length of the stem 5 is preferably terminated at the lower end of 65 the sleeve as best shown in Figure 1 and with its opposite end made in an enlarged head 8. The top of the head is generally flat and square with a fiber insulating plate 9 of the same shape carried upon the same 70 to insulate the binding posts 10.

In the old style plugs only one central electrode is used and the spark between the 75 sparking end of the same and the ground electrode is never intensified to the desired degree that danger of fouling is reduced to a minimum, therefore with our device we propose to use a plurality of central electrodes preferably five in number and including a relatively large center one 11 with 80 four smaller ones 12 grouped around the center one in squared formation. All of the electrodes extend through channels made to receive them in the porcelain and terminate slightly beyond the lower end 85 of the porcelain stem and with the extreme ends of the four smaller electrodes bent inwardly toward the center one 11. The upper ends of all extend through the head 8 of the porcelain and the plate 90 9 with the binding posts 10 adapted to secure the wire leads 13.

In order that the plug may function properly or in other words to ground any selective two of the smaller electrodes we 95 use a clip 14 shaped somewhat like a T so that the head strip 15 thereof may be clamped under the plate 9 in contact with two of the electrodes and with the leg 16 extending down the side of the porcelain 100 head with its end slipped within the metal bushing 4.

The main lead to the plug is divided at an appropriate place so that two wires 17 and 18 lead to two of the smaller electrodes 105 and when the other two small electrodes are grounded by the clip 14, the spark will jump to the center electrode 11 and then to the two grounded ones thus obtaining a four way spark or four distinct sparks at 110

one time. The wires 17 and 18 may include switches 19 and 20 in their circuit so that if desired one of the smaller electrodes may be left dead. Instead of leading the two wires 17 and 18 to two of the smaller electrodes one of them may be connected to the center one 11 in fact with this arrangement various different combinations may be selected.

10. A device embodying this principle will greatly intensify the spark and insure firing of the charge under all conditions.

It is to be understood that the form of our invention herewith shown and described is to be taken as a preferred example of the same, and that various changes in the shape, size and arrangement of parts may be resorted to without departing from the spirit of the invention or the scope of 20 the subjoined claims.

Having thus described our invention, we claim:—

1. A spark plug having a plurality of electrodes arranged in spaced relation, one 25 of said electrodes positioned concentric to a circle including the other electrodes, and spark plug gaps between the concentric electrode and each of the others, said electrodes being carried by a porcelain which 30 in turn is mounted in a metal sleeve made

to be received in the spark plug opening of an engine, and means on the end of each of the electrodes for connecting a lead wire.

2. In a spark plug, an insulated core, a plurality of electrodes carried thereby, one 35 of said electrodes being positioned concentric to a circle including the other electrodes, means for selectively grounding two of the electrodes with the others connected to an ignition system to affect a spark gap between them and the concentric electrode and between the concentric electrode and the grounded ones.

3. In a spark plug, an insulated core, a plurality of electrodes carried thereby, one 45 of said electrodes being positioned concentric to a circle including the other electrodes, means for selectively grounding two of the electrodes with the others connected to an ignition system to affect a spark gap between them and the concentric electrode and between the concentric electrode and the grounded ones, 50 said grounding means comprising a clip connecting two of the electrodes with the metal of the plug. 55

In testimony whereof we affix our signatures.

WILLIAM H. CHARD.
